CLAIM

The ornamental design for a joystick for a work vehicle, as shown and described.

DESCRIPTION

FIG. 1 is a front elevational view of a joystick for a work vehicle showing our new design;

FIG. 2 is a right plane view of a joystick for a work vehicle;
FIG. 3 is a left plane view of a joystick for a work vehicle;
FIG. 4 is a front plane view of a joystick for a work vehicle;

FIG. 5 is a rear plane view of a joystick for a work vehicle;
FIG. 6 is a top plan view of a joystick for a work vehicle;
and,

FIG. 7 is a bottom plan view of a joystick for a work vehicle.
The broken line representations in the figures show unclaimed environment or boundaries, and thus form no part of the claimed design.

1 Claim, 7 Drawing Sheets
